UNITED STATES PATENT OFFICE.

JOHN M. CULLEY, OF JEFFERSON, IOWA.

IMPROVEMENT IN SEEDING-MACHINES.

Specification forming part of Letters Patent No. 131,253, dated September 10, 1872.

To all whom it may concern:

Be it known that I, J. M. CULLEY, of Jefferson, in the county of Green and State of Iowa, have invented a new and Improved Seeding Attachment for Cultivators; and I do hereby declare the following to be a full, clear, and exact description of the same, reference being had to the accompanying drawing forming part of this specification, in which—

Figure 1 is a perspective view of the attachment partly broken away to show the construction, and Fig. 2 is a front view of one of the grain-feeders detached from the hopper.

Similar letters of reference in the accompanying drawing denote the same parts.

My invention relates to that class of seeding-machines in which a series of feed-wheels are placed within a hopper to lift and discharge the grain therefrom when rotated; and has for its object to improve the construction of such machines, whereby they are rendered more complete and efficient in operation. To this end the invention consists, first, in inclosing each wheel within a separate compartment whose upper half is adapted for removal, the grain being fed to the wheel beneath the walls of the compartment only. By this construction the hopper can be completely filled with grain without interfering at all with the movements of the wheels, while the latter are accessible for adjustment or repairs by removing the upper portions of the compartments. It consists, secondly, in the construction of the devices by which the grain is fed from the hopper to the wheels. It consists, thirdly, in the combination of the feeding devices and the seed-slides with the inclosing compartments and the feed-wheels, as I will now proceed to describe.

In the accompanying drawing, A is the hopper of a seeding-machine, and B the feed-wheels, mounted at intervals upon a horizontal shaft, C, having its bearings in the ends of the hopper. Each of the wheels is contained in a narrow transverse compartment composed of lower fixed walls or partitions D, which afford additional bearings for the wheel-shaft, and upper removable sections or boxes E, which fit over the wheels and extend to the top of the hopper. The removable sections rest snugly upon the walls D, and are held in place against lateral displacement by fitting their open ends

over blocks F affixed to opposite sides of the hopper, as shown in the drawing. g are narrow spaces between the walls D and the bottom of the hopper, through which the grain from the latter is fed to the lifting-wheels; and H H are slides passing through the front of the hopper and extending along the outside of each wall D, beneath guide-plates I, so as to close the feed-openings. The slides are constructed in one piece for each compartment, the central portion being outside the hopper in front of the seed-tube J, while the arms pass each side of such tube through the front of the hopper, as above described. By moving the slides through the front of the hopper the size of the feed-openings is adjusted to regulate the quantity of grain fed to the lifting-wheels. K K are cams pivoted to the front of the hopper so as to be turned against one arm of each slide for the purpose of holding the latter in the desired position. L are the feeders, mounted at different angles upon the shaft C, in close proximity to the outside of the compartment-walls. They are each composed of a bar of wood or metal, having beveled edges extending about half their length upon opposite sides. These beveled or sharpened edges are made in the form of a reverse curve, m, as shown in Fig. 2, the outer portion of the curve being flush or nearly so with the flat side n of the bar. By this construction, when the shaft is rotated the bars not only stir the grain in the hopper but force it with a pushing action through the feed-openings g into the compartments of the lifting-wheel. The feed-wheels B are constructed with a series of peripheral shoulders, o, upon which are arranged curved plate P, secured in place by the removable bolts or set-screws q. By this construction buckets or seed-cups are formed upon the wheel, as shown, to lift the requisite quantity of grain. I design to supply the machine with two or more sets of seed-cups, the several sets differing in size somewhat, and to substitute one set for another when it becomes necessary or desirable to change the quantity of seed to be sown.

When the machine is in operation with the hopper filled and the compartments closed, the rotation of the shaft C causes the bars L to feed the grain into the wheel-compartments, where it is taken up by the buckets and dis-

charged into the seed-tube through the openings R in the front of the hopper. By constructing the hopper with compartments, as above described, the feed-wheels are rendered accessible for repairs, &c. The hopper can be completely filled with grain without obstructing the movements of the feed-wheels, because such grain is fed to the wheels at the bottom of the compartments only.

Having thus described my invention, what I claim is—

1. The closed compartments for the feeding-wheels, consisting of the fixed walls D and the removable box F, arranged transversely of the hopper A, substantially as described, for the purpose specified.

2. The feed-bars L, constructed as described, with beveled edges extending about one-half their length upon opposite sides, each edge being formed with a reverse curve, m, the outer portion of which is flush or nearly so with the flat side n of the bar, substantially as herein shown and described, for the purpose specified.

3. The combination of the feed-bars L and adjustable slides H with the feed-wheels and their inclosing-compartments, substantially as described, for the purpose specified.

JOHN M. CULLEY.
